DES. 2100

Letters Patent No. 2100. Dated June 18-1865.

Design for the flanges of a stove.

The schedule referred to in these Letters Patent and making part of the same

To all whom it may concern:

3. It is known that Phineas Smith, of the City and County of New York, in the State of New York, have originated and designed a new pattern for ornamenting and perforating the flanges or projecting webs in gas stoves, of all sorts and sizes, and I hereby declare that the following is a full and exact description thereof.

The accompanying drawings form a part of this specification.

Fig. 1 is a perspective view showing the design applied both to the lower flange and to a higher flange on a stove.

Fig. 2 is a plan view of a portion of a flange on a larger scale.

The letters refer to like parts in both figures.

A is the material of the flange and B and C are holes through the same. The holes B and C together form a continuous series extending along the flange as far as may be required. The hole B is in a diamond form. The hole C is in a circular form. The holes B and C alternate so as to produce a distinct mottled effect peculiar to the stoves of my manufacture and by which my goods will be readily and clearly known from others.

I apply this design to stoves of various sizes, in some instances applying only one flange so distinguished and in others applying two or more so distinguished. I also apply the same to stoves having two or more holes for kettles as well as those having only one hole for one kettle. But in all cases I alternate the diamond shaped holes with the circular holes so as to correspond with the drawing and to form the peculiar ornamental and distinguishing mark or characteristic.

DES. 2100

2

What I claim is, The design or distinguishing
ornamental perforations herein described applied to or in-
cuted in the flanges of gas-tubes in the manner herein shown
and described.

In testimony whereof I have hereunto subscribed my
name in the presence of the subscribing witnesses.
